(57) **CLAIM**

The ornamental design for a product dispenser, as shown and described.

DESCRIPTION

FIG. 1 is a top, front, and right side perspective view showing our new design;

FIG. 2 top, rear, and left side perspective view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is a left side elevational view thereof;

FIG. 8 is a right side elevational view thereof;

FIG. 9 is a top, rear, and left side perspective view thereof wherein a portion of the cover is shown in an open position; and,

FIG. 10 is a top, front, and left side perspective view wherein the opener portion of the cover is shown in an open position.

The broken lines shown in the drawings are included for the purpose of illustrating environmental structure that forms no part of the claimed design.
